UNITED STATES PATENT OFFICE

OTTO ALTBENBACH, OF LOS ANGELES, CALIFORNIA

POCKET IMPLEMENT

Application filed May 17, 1927. Serial No. 192,029.

This invention relates to tools or implements such as folding pocket knives.

In my prior application, Serial No. 186,703, filed April 26, 1927, and entitled "Pocket 5 or folding knife" I describe a folding knife in which the spring of the knife projects beyond the bolster thereof at one end, and is fashioned into a tool capable of use as a screw-driver, a wedge, a wrench, or a glass breaker. It is one of the objects of my invention to improve in general the device shown in that application.

It is another object of my invention to make it possible to cover the exposed end of 15 the blade spring so as to prevent injury to the pockets by the tools formed at the ends of the spring.

My invention possesses many other advantages, and has other objects which may be 20 made more easily apparent from a consideration of several embodiments of my invention. For this purpose I have shown a few forms in the drawings accompanying and forming part of the present specification. 25 I shall now proceed to describe these forms in detail, which illustrate the general principles of my invention; but it is to be understood that this detailed description is not to be taken in a limiting sense, since the 30 scope of my invention is best defined by the appended claims.

Referring to the drawings:

Fig. 1 is a side view of a knife, with one handle removed to expose the blade, and with 35 the tool guard incorporating my invention shown in section thereon;

Fig. 2 is a developed sectional view taken along curved plane 2—2 of Fig. 1;

Fig. 3 is a fragmentary side view of the 40 knife showing the external appearance of the guard;

Fig. 4 is a perspective view of a detail utilized in connection with one form of the guard;

Fig. 5 is a fragmentary sectional back view 45 of a knife illustrating another form of my invention; and

Fig. 6 is a fragmentary side view of a knife illustrating still another form of my invention.

In the form illustrated in Figs. 1 to 4, I show a folding knife blade 11 pivoted at 12, the pivot extending through the handle member 13. The spring 14 for holding the blade 11 either in closed or open position in the 55 well-known manner, extends at the left beyond the handles of the knife. It is formed into a tool, as for example by the aid of the notches and grooves such as 15. This extremity is in general circular.

In order to cover this tool end when not in use and so as to make it convenient for carrying it in the pocket, I provide a folding cover. In the form of Figs. 1 to 4, this 60 folding cover consists of a series of nested U-shaped sections 16, 17, 18, 19 and 20. The largest section 16 is shown as fastened as by rivets 21 to the spring 14; and handles 13 are cut away as shown in Fig. 3 to provide a 65 space for these sections when in telescoped position. The smaller telescoping sections, one of which is shown in greater detail in Fig. 4, are each pivotally movable at their inner ends on a pin 22, and are each provided with sector-shaped sides. They can all nest 70 inside of the stationary section 16, and are 75 in that position while the tool is in use.

However, when the knife is to be carried in the pocket, the cover sections are in the position shown in Figs. 1 and 3. The smallest 80 section 20 carries a snap 23 which projects 85 into a corresponding notch 24 in the upper portion of the spring 14. In order to ensure that the sections will take the circular form illustrated, and form a continuous guard or cover, they are provided with overlapping edges 25, 26. These edges extend at substantially right angles or radially, to the arcuate portion 27 (Fig. 4) of the sections, and adjacent their ends. The edge 25 extends outwardly and is arranged to contact with the inwardly projecting edge such as 26 of the adjacent, larger section. Due to the provision of these overlapping edges, it is assured 90 that as the smallest section 20 is extended out of the stationary section 16, all the other movable sections must follow and form the structure shown in Figs. 1 and 2.

In order to ensure retention of the movable sections in the section 16, the sides thereof 95

contact frictionally with each other. Thus the nested cover sections are held out of the way while the tool is in use.

The covers can take other forms beside that shown. Thus in Fig. 5, I show the tool end 28 of a knife spring 29, that is arranged to be covered by a pair of half shells 30 and 31. These can snap together at their meeting edges, as shown at 32. They are hinged at 10 their back edges to the knife bolsters 33, as indicated at 34.

In Fig. 6 I illustrate still another form of guard or cover, for the projecting tool end 35 of the knife 36. In this form, I show a 15 shell-like, semicircular guard 37 made from thin sheet-metal. It is hinged at 38 to the upper edge of the knife bolster 39. At its other edge, the guard carries a spring snap 40 which can engage into an appropriate 20 notch in the lower portion of spring 41.

I claim:

1. A pocket knife, having a tool at one end, and a guard for the tool comprising a plurality of pivoted sections forming a continuous cover.
2. A pocket knife, having a tool at one end, and a cover member for covering the tool when not in use, comprising a series of sector-shaped sections pivoted on a common axis.
3. A pocket knife, having a tool at one end, and a cover member for covering the tool when not in use, comprising a series of sector-shaped sections pivoted on a common axis, said sections when open, nesting together.
4. A pocket knife, having a tool at one end, and a cover member for covering the tool when not in use, comprising a series of sector-shaped sections pivoted on a common axis, at least some of said sections having edges which 40 contact with edges on adjacent sections for ensuring that they will form a continuous guard.
5. A pocket implement having a tool at one end, and a cover for the tool, comprising 45 a stationary U-shaped section having sector-shaped sides, and a series of progressively smaller sections shaped similarly to the said stationary section, but pivotally movable about a common axis, and capable of all nesting in said stationary section, said section at one edge having an inward projection, the next smaller section having an outward projection arranged to contact with said inward projection to ensure a slight overlapping of 50 these sections when fully extended, the succeeding sections at their overlapping edges being likewise provided with cooperating projections.

In testimony whereof I have hereunto set 60 my hand.

OTTO ALTBENBACH.
